UNITED STATES PATENT OFFICE.

CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 6, 1927. Serial No. 159,300.

My invention relates to railway traffic controlling apparatus, and particularly to apparatus of the type comprising train carried governing means controlled by energy 5 received from the trackway.

I will describe one form of railway traffic controlling apparatus embodying my invention, and will then point out the novel features thereof in claims.

10 The accompanying drawing is a diagrammatic view illustrating one form of railway traffic controlling apparatus embodying my invention.

Referring to the drawing, the reference 15 characters 1 and 1^a designate the track rails of a stretch of railway track over which traffic normally moves in the direction indicated by the arrow. The rails are divided, by means of insulated joints 2, to form a 20 plurality of track sections, only one of which, A—B, is shown in the drawing. A trackway signal S is located adjacent point B and is controlled in accordance with traffic conditions in advance of this point by 25 means forming no part of my present invention and omitted from the drawing for the sake of simplicity. This signal may be of any suitable form and is here shown as a semaphore signal capable of displaying a 30 caution, a proceed or a stop indication. Associated with signal S is a circuit controller D comprising a movable lever 3 arranged to swing into engagement with contacts 4, 5 or 6, according as signal S indicates proceed, caution or stop, respectively.

Train controlling current is at times supplied to the rails of section A—B by a track transformer T. Primary 7 of this transformer is constantly supplied with alternating current from secondary 9 of a line transformer L, the primary 10 of which is supplied with alternating current from an alternator M.

40 Associated with transformer T is a slow-releasing relay R. This relay is connected directly with secondary 9 of transformer L over its own back contact 11. The relay therefore operates intermittently, but due to the slow releasing characteristics of the relay 45 the front contact 12—12^a is closed for a longer interval of time than back contact 12—12^b during each complete cycle of oper-

ation of the relay. To state the matter in another way, the front contact 12—12^a is closed for a greater proportion of a given 55 interval of time than is back contact 12—12^b.

The supply of train controlling current to the rails of section A—B by secondary 8 of transformer T is controlled by circuit controller D. The left-hand terminal of secondary 8 of transformer T is constantly connected with rail 1^a of section A—B. When signal S indicates proceed the right-hand terminal of secondary 8 of transformer T is connected, through contact 3—4 of circuit controller D and front contact 12—12^a of relay R, with rail 1 of section A—B. When signal S indicates caution, the right-hand terminal of secondary 8 of transformer T is connected with rail 1 of section A—B over 60 contact 3—5 of circuit controller D and back contact 12—12^b of relay R. It will be seen, therefore, that train controlling current is supplied to the rails of the section over a front contact or a back contact of relay R 65 according as signal S indicates proceed or caution, respectively. Relay R operates intermittently however as has been explained hereinbefore. It follows that when either of the circuits just described is closed, current is supplied to the rails of section A—B 70 in the form of code impulse combinations made up of impulses of energy separated by time intervals. The relative proportions of a given interval of time that alternating current is supplied to the track rails for the code impulse combinations corresponding to the proceed and caution indications of signal S, may be regulated by properly designing the relay R. For example, I will assume 75 that a complete cycle of operations of relay R occupies one second and that front contact 12—12^a is closed for $\frac{2}{3}$ of a second and back contact 12—12^b is closed for $\frac{1}{3}$ of a second during each such complete cycle. 80

When signal S indicates proceed, therefore, code impulse combinations are supplied to the trackway according to the proceed code which comprises impulses of energy each lasting for $\frac{2}{3}$ of a second and separated by time intervals of $\frac{1}{3}$ of a second. When signal S indicates caution, however, code impulse combinations are supplied to the trackway according to the caution code which 85

comprises impulses of energy of $\frac{1}{3}$ of a second duration separated by time intervals of $\frac{2}{3}$ of a second.

When signal S displays a stop indication, 5 the right-hand terminal of secondary 8 of transformer T is connected directly with rail 1 of section A—B over contact 3—6 of circuit controller D. Under these conditions, 10 alternating current is supplied to the rails of section A—B without interruption.

The reference character V designates a train which is provided with receiving apparatus referred to in general by the reference character W. This receiving apparatus 15 comprises two magnetizable cores 13 and 13^a disposed above the two track rails 1 and 1^a respectively, and located in advance of the forward axle of the train. Core 13 carries a winding 14 and core 13^a 20 is provided with a similar winding 14^a, the two windings 14 and 14^a being connected in series in such manner that the voltages induced therein by alternating currents flowing in opposite directions in the two track 25 rails at an instant are additive. The windings 14 and 14^a are connected through a suitable amplifier 15 and a rectifier 46 with a direct current relay J. It follows that 30 when alternating current is being supplied to the rails of the section occupied by the train, relay J is energized, and that when this supply of current is interrupted relay J becomes de-energized.

Relay J controls a polarized relay K comprising a core made up of a back strap 16 and two legs 17 and 19. The relay also comprises a polarized arm 18 which is supplied with uni-directional magnetic flux. The arm 18 may be a permanent magnet, 40 but as here shown is provided with a winding 35 which is supplied with current as will be described in detail hereinafter. An armature 20 of magnetizable material is pivoted to arm 18 and is arranged to be 45 swung toward one or the other of legs 17 or 19 in accordance with the distribution of the magnetic flux in the core of the relay. The armature may be biased to a central 50 position by means not shown in the drawing. Operatively connected with the armature 20 is a movable contact finger 21 adapted to close contact 21—21^a or 21—21^b according as the armature 20 is swung toward the leg 19 or leg 17, respectively. Leg 17 55 of relay K is provided with a winding 27 and leg 19 is provided with a similar winding 25, windings 25 and 27 being connected in series in such manner that when current is supplied to these windings the magnetic fluxes created in the core traverse a magnetic path through leg 17, back strap 16, leg 19, and armature 20 in the same direction.

When relay J is energized, current flows 60 from a suitable source of direct current such as a battery P through wire 22, front con-

tact 23 of relay J, wire 24, winding 25, wire 26, winding 27, wire 28, primary 29 of a transformer C, wires 31 and 32, front contact 33 of relay J, wire 34, winding 35, and wires 36, 37, 38 and 39, back to battery P. When this circuit is closed the flux created by windings 27 and 25 is in such direction with respect to the flux created by winding 35 that these fluxes are additive in the magnetic circuit including the arm 18, back strap 16, leg 19 and armature 20, but that the fluxes are in opposition in the magnetic circuit including leg 17, back strap 16, arm 18, and armature 20.

When relay J is de-energized, current flows 80 from battery P, through wire 22, back contact 23 of relay J, wires 40 and 31, primary 29 of transformer C, wire 28, winding 27, wire 26, winding 25, wire 24, back contact 33 of relay J, wire 34, winding 35, and wires 36, 37, 38 and 39, back to battery P. It will be plain that under these conditions, the direction of the current in windings 27 and 25 is reversed but that the direction of the current in winding 35 is the same as 90 when relay J is energized. When the circuit just traced is closed, a surge of magnetic flux is created in the core of the relay K which is in such direction with respect to the flux created in the core of the relay 95 by winding 35 that the fluxes are additive in the circuit including leg 17, back strap 16, arm 18, and armature 20 but that these fluxes are in opposition in the circuit including arm 18, back strap 16, leg 19, and armature 20. It follows that the intermittent operation of relay J due to the caution or proceed codes in the trackway causes surges of magnetic flux in opposite directions in the core of the relay K. The flux 105 created in relay K when relay J is energized tends to draw armature 20 toward leg 19, and the flux which is supplied to the relay K when relay J is de-energized tends to draw armature 20 toward leg 17. But 110 when relay J is receiving the proceed code, the relay is energized for a greater proportion of a given interval of time than it is de-energized, so that the predominating influence upon the armature 20 is to draw 115 this armature toward leg 19. When relay J is receiving the caution code, however, it is de-energized for a greater proportion of a given interval of time than it is energized and under these conditions armature 20 is 120 drawn toward leg 17.

The secondary 30 of transformer C is connected through a rectifier 41 with a relay G. It will be manifest that each operation of relay J reverses the direction of the flux 125 created in the core of transformer C by current in winding 29 and it follows that alternating current is created in secondary 30 of this transformer when relay J is being operated intermittently. The alternating 130

current created in secondary 30, rectified by 41, energizes relay G and it follows that relay G is energized only when relay J is being operated intermittently.

5 The train is provided with governing means of any suitable type and as here shown this governing means comprises three electric lamps 43, 44 and 45, arranged when lighted to indicate proceed, caution and stop, respectively. Lamp 43 is connected with battery P over front contact 42-42^a of relay G and contact 21-21^a of relay K. Lamp 44 is connected with battery P, over front contact 42-42^a of relay G and contact 21-21^b of relay K. The stop lamp 45 is connected with battery P over back contact 42-42^b of relay G.

In explaining the operation of the apparatus as a whole, I will first assume that signal S indicates proceed, as shown in the drawing, so that train controlling current is being supplied to the track rails in accordance with the proceed code. Relay J is therefore intermittently operated so that its front contacts and back contacts are alternately closed for intervals of $\frac{2}{3}$ of a second and $\frac{1}{3}$ of a second, respectively. It follows that the effect of the magnetic surges created in the core of relay K by the current which is supplied to windings 27 and 25 during the interval of time that relay J is energized is predominating, and armature 20 is therefore drawn toward leg 19, so that contact 21-21^a is closed. Furthermore, the periodically reversed current supplied to primary 29 of transformer C causes relay G to become energized and closes its front contacts. Lamp 43 is therefore lighted to indicate proceed.

40 I will next assume that signal S indicates caution so that train controlling current is supplied to the rails of section A-B in accordance with the caution code. Relay J is then operated intermittently, but the back contacts of this relay are now closed for a greater proportion of a time interval than are the front contacts of this relay. The surge created in the core of relay K during the first de-energization of relay J tends to counter-act the flux created by winding 35 in the magnetic circuit including leg 19, and also tends to build up the flux in the circuit including leg 17. It may happen that the surge of flux supplied during the first de-energization of relay J is not sufficient to cause the flux through leg 17 to predominate sufficiently over the flux through leg 19 to reverse armature 20. But each successive de-energization of relay J causes an increasing proportion of flux to flow through leg 17 and armature 20 and the action of the relay is therefore to integrate the magnetic surges in the core, and to build up the relative average flux in leg 17 to a higher value than that in leg 19.

When the relative average flux in leg 17 predominates over that in leg 19 the armature 20 is reversed, swinging toward leg 17 and closing contact 21-21^b. Relay G is of course energized so that this operation of relay K lights lamp 44 to indicate caution.

When signal S indicates stop, uninterrupted alternating current is supplied to the rails of section A-B, and relay J is continuously energized. Under these conditions, the armature 20 of relay K will remain in the position to which it was last moved, but relay G will be de-energized and lamp 45 will be lighted. Furthermore, should the supply of alternating current to the rails for any reason be interrupted or should relay J become de-energized for any other reason, relay G will also become de-energized and the stop lamp 45 will be lighted. It should also be pointed out that any break in the circuit including windings 27 and 25, or any defect in the contacts of relay J will prevent the supply of current to relay G and allow this relay to become de-energized to display a stop indication on board the train.

One feature of my invention is the provision of apparatus which is responsive to the relative average values of the code impulses which comprises the train controlling current. In case of any variation in the absolute lengths of these impulses, or of the time intervals separating successive impulses, the only effect upon the operation of relay K is that a longer time interval might be required upon a change from one code to another before the integrating action of the relay could build up a sufficiently predominating flux through one leg to reverse the armature. In the particular embodiment of my invention here shown, the relays J and G are both direct current relays supplied with energy through rectifiers, but this particular arrangement is not essential.

Although I have herein shown and described only one form of railway traffic controlling apparatus embodying my invention, it is understood that various changes and modifications may be made therein within the scope of the appended claims without departing from the spirit and scope of my invention.

Having thus described my invention, what I claim is:

1. In combination, a relay comprising a core having a first magnetic circuit, a magnetized member on the core forming a part of two other magnetic circuits, means for creating in the first magnetic circuit alternately reversed surges of magnetic flux of unequal lengths, and a movable member responsive to the relative average values of the fluxes in the said two other magnetic circuits.

2. In combination, a relay comprising a

core having two magnetic circuits, means for supplying uni-directional flux to both said circuits, means for creating in the two circuits alternately reversed surges of magnetic flux of unequal lengths, and a movable member responsive to the relative average values of the fluxes in the two circuits.

3. In combination, a relay comprising a core having two magnetic circuits, means for supplying uni-directional flux to both said circuits, means for creating in the two circuits alternately reversed surges of magnetic flux of unequal lengths, a movable member responsive to the relative average values of the fluxes in the two circuits, a second relay energized only when such surges are being supplied to the first relay, and governing means controlled by the movable member and by the second relay.

4. In combination, two magnetic circuits supplied with uni-directional flux, means for creating in the two circuits alternately reversed surges of magnetic flux of unequal lengths, means for varying the relative lengths of the surges to vary the distribution of the fluxes in the two circuits, and a movable member responsive to the relative average values of the fluxes in the two circuits.

5. In combination, a relay comprising a core having two magnetic circuits, means for supplying uni-directional flux to both said circuits, means for creating in the two circuits alternately reversed surges of magnetic flux of unequal lengths, and a movable member controlled jointly by the fluxes in said two circuits.

6. Railway traffic controlling apparatus comprising a train carried relay, means located partly in the trackway for energizing the relay in such manner that the periods

of energization and de-energization of the relay occupy different proportions of a given interval of time, a core having two magnetic circuits each including a magnetized member, means controlled by the relay for creating in said two circuits alternately reversed surges of magnetic flux, and a movable member controlled jointly by the fluxes in said two circuits.

7. Railway traffic controlling apparatus comprising a train carried core having two magnetic circuits, means for supplying uni-directional flux to both said circuits, means located partly in the trackway for creating in said two circuits alternately reversed surges of magnetic flux of unequal lengths, a movable member controlled jointly by the fluxes in said two circuits, and governing means controlled by said member.

8. Railway traffic controlling apparatus comprising means for supplying the trackway with interrupted alternating current in such manner that current flows in the trackway for different proportions of a given interval of time, a first train carried relay responsive to such current in the trackway, a transformer having a secondary and a primary, a second relay receiving energy from said secondary, a core comprising two magnetic circuits, and two windings, one on each magnetic circuit; an electrical circuit including a source of energy, the primary of the transformer, a pole-changing contacts on the first relay, and said two windings; a movable member controlled jointly by the fluxes in said two magnetic circuits, and governing means controlled by the second relay and by the movable member.

In testimony whereof I affix my signature.

CLARENCE S. SNAVELY.
